UNITED STATES PATENT OFFICE

JOSEPH DESTREE, OF BRUSSELS, BELGIUM

FIREARM

Application filed April 5, 1930, Serial No. 442,003, and in Belgium April 13, 1929.

The present invention relates to a firearm in which the breech recoils under the action of the pressure of the gases and in particular to a firearm in which this movement of recoil of the breech already takes place during the whole of the time that the projectile is still in the barrel.

The object of the invention is to soften the recoil movement of the breech.

10 For this purpose, the invention provides for this movement of recoil to be damped by the gases taken from the barrel at a distance from the breech at least equal to a number of times the length of the cartridge.

15 The invention provides in particular for these shock absorbing gases to act on a member connected mechanically to the breech, the said gases tending to displace this member in the reverse direction to the recoil of the

20 breech.

Other details and features of the invention will appear from the course of the description of the accompanying drawings which illustrate diagrammatically in perspective

25 two forms of construction of the invention.

Figure 1 is an axial section with parts cut away of the barrel and of the breech of a firearm with internal recoil provided with a breech damping device according to the in-

30 vention.

Figure 2 is an axial section of a modified form of the invention.

Referring more particularly to Figure 1, this figure shows the barrel 2 of a firearm the 35 interior of which communicates through a duct 3 with the cylinder 4. This duct 3 is situated at a distance from the breech at least equal to a number of times the length of the cartridge 8.

40 In the case shown this duct is even situated near the back part of the barrel.

This cartridge comprises a cylindrical case to prevent it from deforming and bursting during the time it recoils under the pressure 45 of the gases which are still in the barrel.

The gases admitted into the cylinder 4 through the duct 3 act on a piston 5 connect- 50 ed by a rod 5a to the breech 6.

55 In the case shown, the latter is never locked. Its movement of recoil under the

action of the gases which expel the projectile, by being damped by the action of the gases acting on the piston 5 is particularly gentle. Consequently the mass of the breech which is fairly great when the damping action according to the invention is not applied, may be reduced to a considerable extent.

55 In order to permit the suitable recoil of the breech 6, the invention provides for the braking action of the gases acting on the piston 5 to be reduced. This reduction may be obtained by reducing the pressure of these gases, for example by drawing off the shock absorbing gases from near the outlet end of the barrel.

60 This reduction in pressure may also be effected by providing holes such as 4a in the cylindrical wall 4.

65 Instead of connecting the breech 6 to a piston moving under the action of the gases in a cylinder, it may also be connected by a rod 5a as shown in Figure 2, to a sleeve 7 arranged at the outlet end of the barrel 2. This sleeve 7 has an aperture 7a larger than the internal diameter of the barrel 2. Its 70 form is such that the jet of gas issuing from the barrel will have a tendency to carry it in the reverse direction of movement to that of the recoil of the breech.

75 Whatever be the arrangement adopted, the 80 shock absorbing gases cease to act at the same time as those which produce the recoil of the breech, because they are in free communication with the interior of the barrel.

It is obvious that the invention is not ex- 85clusively limited to the form of construction shown and that many modifications may be made in the shape and in the arrangement of the members employed in its construction without going outside the scope of the pres- 90ent invention.

95 It is further obvious that the braking de- vice according to the invention may be applied to other breech blocks than those which are never locked, provided that these breech blocks recoil under the action of the pressure of the gases in the barrel. These breech blocks may for example recoil after a releasing action itself effected by the action of the gases.

What I claim is:

1. An automatic firearm comprising a breech which recoils under the pressure of the gases in the barrel, a movable member, means for connecting positively this movable member with the breech and means for leading the gases in the barrel from a point of the latter at a distance from the breech equal to a number of times the length of the cartridge case onto the face of this movable member to damp the recoil of the breech directly by the gases.

2. An automatic firearm comprising a breech which recoils under the pressure of the gases in the barrel, a movable member, means for connecting positively this movable member with the breech, and means for leading the gases in the barrel from a point near the outlet of the latter onto the face of this movable member to damp the recoil of the breech directly by the gases.

3. An automatic firearm comprising a breech which recoils under the pressure of the gases in the barrel, a movable member disposed near the outlet of the barrel, means for connecting rigidly this movable member with the breech, and means for leading the gases in the barrel from a point near the outlet of the latter onto the face of this movable member to displace the latter towards the outlet of the barrel.

In testimony whereof I affix my signature.

JOSEPH DESTRÉE.
